UNITED STATES PATENT OFFICE.

ARTHUR J. ORDING, OF CHICAGO, ILLINOIS.

ELECTRIC HEATER FOR SEALING-WAX.

1,353,972.

Specification of Letters Patent. Patented Sept. 28, 1920.

Application filed October 3, 1919. Serial No. 328,281.

To all whom it may concern:

Be it known that I, ARTHUR J. ORDING, a citizen of the United States, residing at Chicago, in the county of Cook and State of Illinois, have invented certain new and useful Improvements in Electric Heaters for Sealing-Wax, of which the following is a specification.

This invention relates to improvements in a device to be used for heating sealing wax to a sufficient degree to cause the same to melt and for applying the melted wax to articles or packages to be sealed thereby, and it consists in certain peculiarities of the construction, novel arrangement and operation of the various parts thereof, as will be hereinafter more fully set forth and specifically claimed.

As is well known, commercial sealing wax is furnished in the form of sticks or bars, which are usually substantially rectangular in cross-section and in order to melt the same for sealing purposes, one end of the sticks or bars is usually exposed to the heat of a gas jet until the wax is melted, when they are removed from the flame and the melted wax daubed on the package to be sealed. This method of melting and applying the wax is wasteful, as a considerable amount of the wax drops from the stick in heating the same, thus causing its loss and soiling or defacing the table or floor on which it falls. Besides, said method is inconvenient and frequently causes the hands of the user to be burned or soiled.

To overcome these objections and to provide an electric heater for sealing wax by means of which wax can be readily heated to the desired degree and applied in suitable quantities and at the exact places on the packages to be sealed, and then, if desired, to compress the wax by means of a seal carried by the device is one of the objects of my invention.

Another object is to provide a heater for sealing wax which shall be simple and inexpensive in construction, strong, durable and efficient in operation. Other objects and advantages of the invention will be disclosed in the subjoined description and explanation.

In the accompanying drawing which serves to illustrate an embodiment of the invention—

Figure 1 is a plan view of the device.

55

Fig. 2 is a view in side elevation thereof.

Fig. 3 is a plan sectional view taken on line 3—3 of Fig. 2 looking in the direction indicated by the arrows, and

Fig. 4 is a cross-sectional view taken on line 4—4 of Fig. 2 as indicated by the arrows.

Like numerals of reference refer to corresponding parts throughout the different views of the drawing.

65

The numeral 6 designates the container for the wax, which container is made of metal, and by preference in the shape of an elongated and rectangular box. At one of its ends the side walls of the container 6 are inclined toward each other as at 7, see Fig. 1 of the drawing, to provide a tapered spout for the discharge of the melted wax. The free or outer ends of the inclined walls 7 of the container are spaced apart to provide an opening for the outlet of the melted wax. The upper surface 8 of the container connecting the inclined portions or walls 7 thereof is downwardly inclined toward its free end and terminates at the free ends of said side walls. At its opposite end the container 6 is provided in its upper portion with an opening 9 the side walls of which are inclined as shown in Fig. 2 of the drawing. This opening is closed by means of a door 10 which is secured at its inner end by means of hinges 11 of any suitable kind to the upper surface of the container at the upper edge of the opening 9 therein. The door 10 may be provided with a rotary fastener 12 in its rear end to engage the lower portion of the rear end of the container so as to prevent the accidental opening of said door.

80

Near its front or discharging end the container 6 is provided with a forked upright 13 between the prongs 14 of which is pivotally mounted on a pin 15, a lever 16, the rear end of which is provided with a thumb piece 17 by means of which said end of the lever can be depressed. The opposite end of the lever 16 is provided with a hood-shaped door 18 to embrace the free ends of the side walls 7 and the free end of the upper surface 8 of the container so as to close the opening formed by said parts. A U-shaped spring 19 straddles the lever 16 forwardly of the upright 13 and has its ends coiled around

85

100

105

the pin 15 and is used to hold the hood or door 18 in its closed position, as shown by continuous lines in Fig. 2 of the drawing.

The container 6 is mounted on the upper 5 surface of an electric heater, which is designated as a whole by the reference numeral 20 and may be of the ordinary and well known construction of such heaters.

In the present instance, the heater is 10 shown as consisting of a box 21 having located therein a core of mica, which core comprises a pair of parallel pieces 22 united at one of their ends by a part 23 of the same material.

15 Coiled around the core is an electric conducting wire 24 which has its terminals connected to binding posts 25 for other electric conductors 26 and 27 which may lead to a supply of electricity such as the service line 20 or wire for lighting purposes not shown.

The heater 20 is firmly secured to the bottom of the container 6 by means of straps 28 which surround both the container and the heater at suitable points near the middle 25 thereof. Mounted on the upper surface of the container 6 inwardly of each of the straps 28 is an upright bracket 29 each of which has a foot 30 extended under the strap 28 adjacent thereto. Each of the feet 30 is provided with an opening to receive a screw 31 which screws are extended through suitable openings in the straps 28 and engage openings in the top of the container. Thus it will be understood that the straps 28 not only serve to hold the container 6 and heater 20 together, but also hold the brackets 29 in an upright position. The upper ends of the brackets 29 are connected together by means of a handle 32 which may be of non-heat conducting material if desired. Located on the bottom of the heater 20 is a pad 33 of asbestos or other suitable non-heat conducting material which is held in place by means of a strap 34 which surrounds the container 40 6, heater 20, and pad 33 about midway between the brackets 29 and may be fastened to the container 6 by means of a screw 35 engaging the upper surface thereof. At

the middle of its lower portion the strap 34 is provided with a depending projection 36 50 on the lower end of which is mounted a seal 37 of any desired design which can be used for compressing the melted wax after it has been applied to the package or article to be sealed. 55

From the foregoing and by reference to the drawing, it will be readily understood and clearly seen that by opening the door 10, one or more sticks or bars of wax can be inserted into the container 6 when said door 60 may be closed and held in its closed position by means of the catch 12 thereon. The switch controlling the flow of electric current to the heater 20 can then be turned on, when it is apparent that the wax will soon be heated 65 to a melting degree by reason of the heat generated from the electric heater, and that it can be discharged from the discharging end of the container 6 in the desired quantities and at the desired places by pressing 70 downwardly on the thumb piece 17 of the operating lever 16 which controls the operation of the door 18 for said end of the heater.

The container 6 may be provided at a suitable point but preferably in its upper surface with a vent opening 38, which by preference is located near one end of the handle as is clearly shown in Fig. 1 of the drawing. 75

Having thus fully described my invention, what I claim as new and desire to secure by 80 Letters Patent is—

In a device of the character described, the combination with an electric heater, of a handled container mounted thereon and having a tapered and cross-sectionally angular 85 discharge nozzle at one of its ends and an opening for the insertion of wax at its other end, a door to close the last named opening, a spring actuated lever fulcrumed on the container near its discharging nozzle, a cross-sectionally angular door on said lever 90 to close the opening in said nozzle, a seal mounted on the heater at a distance therefrom and non-heat-conducting material interposed between the seal and heater. 95

ARTHUR J. ORDING.
